FIG. 6.

Inventor
T. E. McGlinoy.

By *A. Murphy Jr.* Attorney

UNITED STATES PATENT OFFICE.

THOMAS E. McGLINCY, OF SWedesboro, NEW JERSEY.

TRAFFIC SIGNAL.

Application filed August 29, 1922. Serial No. 585,010.

To all whom it may concern:

Be it known that I, THOMAS E. McGLINCY, a citizen of the United States, residing at Swedesboro, in the county of Gloucester and

5 State of New Jersey, have invented certain new and useful Improvements in a Traffic Signal; and I do hereby declare the following to be a full, clear, and exact description of the invention, such as will enable others 10 skilled in the art to which it appertains to make and use the same.

This invention relates to a traffic signal.

It is aimed to provide a construction whereby novel means in simulation of the 15 movement of the hand may be provided to indicate to adjacent traffic an intention to turn.

It is particularly desired to provide a 20 novel construction which is compact, inexpensive and durable, which normally occupies a folded position against the car, does not detract from its appearance, and is adapted for use on closed as well as open cars and also when storm curtains are in 25 place.

Specific objects and advantages will be 30 pointed out and will become apparent in the following description of one operative embodiment taken in connection with accompanying drawings illustrating the same.

In said drawings:—

Figure 1 is a view illustrating the invention in perspective and as applied to a wind- 35 shield frame;

Figure 2 is a view of the invention principally in substantially longitudinally central section;

Figure 3 is a detail view illustrating the 40 electric switch employed;

Figure 4 is a detail view of the connection 45 between the operating arm; the signal arm, and

Figures 5 and 6 are detail perspective 50 views of the clasp and clamp used in connection with the invention, and

Figure 7 is a sectional view of the switch, 55 taken on the plane indicated by the line 7—7 of Figure 3.

Like reference characters designate like or 60 similar parts in the different views.

My improvements are adapted to be attached to the frame of the wind shield of an automobile. A wind shield is conventionally shown at A having a frame B and 65 particularly a post C to which the improvements may be connected. In the example

illustrated, the signal is adapted to indicate a left turn. It may be used however to indicate a right turn or one of the signals may be used at each side or end of the wind shield.

The signal includes an arm 10 which carries a semaphore 11, which may be shaped similar to the human hand or otherwise as preferred. A clamp is employed at 12 which 70 has arms or straps 13 in sections pivoted together at 14 and adapted to be fastened at the outermost sections to the arm 10 and clamped at the innermost sections as by means of a bolt 15, rigidly to the post C. 75 The axis of the sections of clamp 12 is horizontal and thus the arm 10 is adapted to be raised in a vertical plane and from a horizontal to a vertical position and vice versa.

A suitable clasp is provided at 16 having 80 separated arms at 17 intermediate which the arm 10 freely moves and by which arms 17 the arm 10 is adapted to be clasped and held. Said arms 17 are preferably of resilient metal and at their inner ends are 85 rigidly clamped by a bolt or the like at 18 to the said post C.

Any suitable means may be utilized in raising and lowering the arm 10. For instance an operating rod 19 is utilized which 90 is slideable through a guide eyelet 20 detachably connected in any suitable manner to said post C. Rod 19 extends through an elongated slot 21 in the arm 10 and within the arm 10 a head or the like 22 is provided 95 on rod 19, thus providing a loose, pivotal or slip connection between arm 10 and rod 19.

As a result, it will be seen that the arm 19 may be raised from the full line position of 100 Figure 1, which is the signaling position and indicates a left hand turn, to the dotted line position in the same figure, which is its normal position. In the latter position, the arm 10 is upheld by the clasp engagement of member 17 therewith. Thus to apply the signal 10 the rod 19 is moved outwardly 105 away from the operator and to restore it to normal position the rod 19 is pulled toward the operator.

The semaphore 11 may carry a suitable lamp at 23, which is preferably an electric lamp and has wires or conductors 24 leading thereto and connected in circuit in any suitable manner with the storage or other battery on the vehicle. Said arm 10 is hollow to accommodate wires 24 and the operating arm or rod 19 is also hollow and wires 110

24 are extended into the same and to an electric switch 25, of any suitable type, at the free end of the arm 19 and which switch is enlarged and adapted to engage the eyelet 5 20 and thus limit movement of the arm 10 to a horizontal or projected position.

The slip connection of the arm 19 at 21 is such as to enable the arm 19 to hang substantially vertically when the arm 10 is 10 raised and in normal position. This is shown in dotted lines in Figure 1.

As merely one practical embodiment has been illustrated and described, it is to be understood that changes in the details may 15 be resorted to provided they fall within the spirit and scope of the invention.

I claim as my invention:—

In signaling mechanism of the class de-

scribed, a signal arm, means to pivotally mount said arm, illuminating means for said arm including a lamp thereon, an operating rod for said arm having slip connection therewith, a guide member through which said operating rod passes, said arm and operating rod being hollow and having conductors to said lamp disposed therein, and a switch associated with said conductors at the operating end of said rod and engageable with the guide member to limit movement thereof and of the arm.

In testimony whereof I affix my signature in presence of two witnesses.

THOMAS E. McGLINCY.
